UNITED STATES PATENT OFFICE.

FRANKLIN BITTNER, OF NEW YORK, N. Y.

DEVICE FOR WINDING RADIOCOILS.

Application filed January 19, 1925. Serial No. 3,419.

To all whom it may concern:

Be it known that I, FRANKLIN BITTNER, a citizen of the United States of America, residing at 81 Irving Place, New York, ⁵ county and State of New York, have invented new and useful Improvements in Devices for Winding Radiocoils, of which the following is a specification.

This invention relates to devices for winding radio coils, and particularly to devices for winding low loss radio coils.

One of the objects of the present invention is to produce an improved skeleton or framework upon which a low loss radio coil can be wound accurately and speedily with the greatest ease and facility, thereby extending its use to the amateur and unskilled, as well as to the skilled.

Specifically, the present invention contemplates the provision of a device which can be assembled in a plurality of ways to produce a plurality of cylindrical supporting surfaces having different diameters, whereby coils of various diameters can be readily wound by merely changing the position and location of the relative parts.

Specifically, the invention further contemplates the provision of a device for winding radio coils which can be readily disassembled without interfering in any way with the coil being wound, thereby facilitating the formation of a coil having uniform honeycomb formations.

These and other features, capabilities and advantages of the invention will appear from the subjoined detail description of one specific embodiment thereof, illustrated in the accompanying drawings, in which—

Figure 1 is a plan view showing the units assembled for a certain diameter.

Fig. 2 is a section on the line 2—2 of Fig. 1.

Fig. 3 is a plan view of the centerpiece.

Fig. 4 is a side elevation of the centerpiece.

Fig. 5 is an elevation of the centerpiece, showing the peripheral openings formed therein in dotted lines.

Figs. 6, 7 and 8 illustrate a plan view, a side elevation and an end elevation respectively, of one of the coil supporting units.

Fig. 9 is a side elevation of one of the securing pins.

Fig. 10 is a side elevation showing one of the supporting units and securing pins secured to one another.

Fig. 11 is a view illustrating diagrammatically several of the various diameters of the supporting surfaces for the coils, and

Fig. 12 is a view illustrating diagrammatically still a different diameter of supporting surface for the coil being wound.

The present invention contemplates the provision of a winding device particularly adapted for forming low loss radio coils. ⁶⁵ To do this, there is provided a centerpiece 1 having an uneven plurality of orifices 2 formed therein for the reception of pins 3.

There is also provided an uneven plurality of wire supporting units 4 which may be secured to the centerpiece by the pins 3. By the relative positioning of the pins, units and centerpiece, one to another, a plurality of winding devices may be produced.

The centerpiece, in the present instance, ⁷⁵ has three cylindrical portions 5, 6 and 7 of different diameters, the cylindrical portion 6 being provided with the orifices 2 and in the present instance having the greatest diameter, and the cylindrical portion 7 having the least diameter. The cylindrical portion 7 is secured to one side of the cylindrical portion 6, and the intermediate sized cylindrical portion 5 is secured to the other side of the cylindrical portion 6. ⁸⁵

The pins 3 of which there are provided an uneven number, are preferably cylindrical in form, as illustrated in Fig. 9. The pins 3, in number, of course correspond to the number of orifices 2. When assembled, the orifices 2 receive the pins 3. The orifices 2, in the present instance, are about one-half inch in depth.

In the present instance, the device is illustrated as comprising thirteen orifices 2 ⁹⁵ and thirteen pins 3, although, of course, it is understood that good results can be obtained with a greater or less number of pins, so long as they are uneven in number.

One type of winding device can be obtained by merely securing pins 3 to the centerpiece 1 without the use of the supporting units 4. In such instance, the periphery of the cylindrical portion 6 will serve as the supporting surface for the coil to be wound. ¹⁰⁵ Of course it is understood that the reason for providing an uneven number of pins is in order to insure the winding of the conductors on the pins so that the wire, when returning to its initial pin, will be directed in the opposite direction around said initial pin so that adjacent layers of the wire will

be spaced from one another throughout the loop portion thereof and only contact with one another in a comparatively small area, see Fig. 1. When the coil winding device 5 consists only of the centerpiece 1 and the pins 3, the inner diameter of the coil will be twice the length defined by the arrow 8 illustrated in Fig. 5, which arrow illustrates the radius of the cylindrical portion 6.

10 With the use of the supporting units 4, a number of other combinations having different diameters can be made. The supporting units 4, as illustrated in Figs. 6, 7 and 8, each consist of a lower anchoring member 9 and 15 a pin member 10. The pin member 10 is preferably cylindrical and has substantially the same diameter as the pin 3. In the present instance, it is shown as having a shorter length than the pin 3. The anchoring member 20 is preferably of the same width as the width of the centerpiece 1. It has two sets of inclined faces, one set comprising the faces 11 and 12, and the other set comprising the faces 13 and 14. The inclination 25 of these faces depends upon the number of pins and supporting units that are used. In the present instance, where only thirteen pins and thirteen supporting units are used, the faces of each set are inclined to one another at about twenty-seven degrees. The 30 end face 15 of each anchoring member, in the present instance, is shown convex, although this is not necessary. It is only necessary that the length from end to end of 35 the faces approximate about one-thirteenth of the periphery of the cylindrical member 6 so that when the anchoring members are secured to said cylindrical portion 6, in the manner indicated in Fig. 12, the face 11 of each anchoring member will engage the face 12 of an adjacent anchoring member and thereby align the anchoring members with one another, around the cylindrical portion 6. Of course, when there are a greater or 40 less number of anchoring members used, the length of the end face 15 will be correspondingly changed. As shown in Fig. 8 a cylindrical opening 16 is formed in the anchoring member extending from the end face 15 45 to the concave face 17. Through these orifices 16 and the orifices 2, the pins 3 extend and thereby help to align and anchor the anchoring members to the centerpiece 1.

50 When the supporting units 4 are used as just described, with the convex faces 15 engaging the periphery of the cylindrical portion 6, as illustrated in Fig. 12, the coils, of course, will be wound on the pins 10 and consequently the radius of the outer supporting surface of the coils will be, as indicated in Fig. 12 by the arrow 26.

55 Adjacent to the concave face 17 a depending portion 18 is formed on each anchoring member, the side faces of which are continuations of the faces 13 and 14 of the anchor-

ing member. The end face 19 of the depending member 18 is also concave. In the present instance, the arcuate length of the concave face 19 is substantially one-thirteenth of the peripheral length of the cylindrical portion 7, and the arcuate length of the concave face 17 of each anchoring member is substantially one-thirteenth of the peripheral length of the cylindrical portion 6. Furthermore, the faces 18 and 19 are also inclined to one another at about twenty-seven degrees. Consequently, when the anchoring members are mounted on the centerpiece 1 with their concave faces 17 in engagement with the cylindrical portion 6 and their concave faces 19 in engagement with the cylindrical portion 7, the anchoring members, as shown in Figs. 1 and 2, will align one another and be in intimate engagement with one another. In this position also, the pins 3 will extend through the orifices 16 into the orifices 2 of the cylindrical portion 6 and there help properly to align and anchor the anchoring member. When the anchoring members are mounted, as illustrated in Figs. 1 and 2 just described, the radius of the outer periphery defined by the convex faces 15 will be, as indicated in Fig. 11 by the arrow 20. When the anchoring members are so mounted, the conductors can also be wound around the pins 10 of the supporting units, in which case, the outer supporting periphery of such conductors will have the radius indicated by the arrow 21 in Fig. 11.

Still further combinations can be contrived. As an instance, as illustrated on the right side of the schematic view, Fig. 11, the concave faces 19 of the anchoring members may engage the cylindrical portion 5 of the centerpiece 1 with the plane faces 22 of the depending portions 18 engaging the face 23 of the cylindrical portion 6 being aligned thereby when the pins 3 extend through the orifices 16 of the anchoring members into the orifices 2 of the cylindrical portion 6. In this position again, two winding surfaces are provided, one adjacent to the pins 3 on the convex faces 15, the radius of which is indicated by the arrow 24, and the other winding surface on the pins 10 the outer periphery of the winding surface having the radius indicated by the arrow 25 in Fig. 11.

These devices are preferably made of aluminum, the centerpiece and anchoring members being cast and the rods cut from cylindrical stock, although obviously, other materials can also be used with good results.

With these devices, it is then apparent that low loss radio coils with various diameters can be wound by merely re-arranging the units to suit the combinations desired. When the coils are formed on the pins 3, the coils can be removed without distortion.

This is readily accomplished by securing the loops of a coil together with silk thread, shellac or the like, as each pin 3 is drawn out. In other words, as each pin 3 is removed the adjacent anchoring member is free to drop out. Thereupon, and before removing the succeeding pin 3, the liberated portion of the coil is secured in position by a silk thread, shellac or the like, whereupon 10 the next succeeding or another pin may be removed, liberating another anchoring member and so on.

Similarly, when the coils are formed on the pins 10, the coils may be removed without distortion. In this latter case, similarly 15 a pin 3 will first be removed, and thereupon the thereby connected anchoring member 9 withdrawn to liberate a portion of the coil, which may then be secured in place by a silk thread, shellac or the like. Thereafter a 20 succeeding or another pin 3 may be removed followed by the anchoring member 9 which has been secured in place by such pin 3.

The removable feature aforesaid constitutes one of the main features of the present 25 invention.

With these devices, low loss radio coils of various shapes may also be produced without regard to the diameter of the same. As 30 an instance, instead of winding the conductors of a coil zig-zag from the left side of one pin to the right side of the succeeding pin and from such right side of the succeeding pin to the left side of the next succeeding pin, the conductors of a coil may pass around the left side of two adjacent pins and then pass to the right side of the next two succeeding pins and so on.

When the pins 3 do not fit snugly in the 40 orifices 2 of the centerpiece 1, good results have been obtained with this device by using a rubber band 27, as illustrated in Fig. 2, encircling the pins 10 whereby the anchoring members 9 and pins 3 are securely located 45 in place.

It is obvious that various changes and modifications may be made to the details of construction without departing from the general spirit of the invention, as set forth 50 in the appended claims.

I claim:

1. A device of the character described having a plurality of pins, a centerpiece provided with a plurality of orifices for removably receiving said pins and to form a forming core for a coil having an inner periphery corresponding to the outer periphery of the centerpiece, and a plurality of anchoring members removably secured in position on said centerpiece by said pins to form a forming core for a coil having an inner periphery corresponding to the outer periphery formed by said anchoring members.
2. A device of the character described having a plurality of pins, a centerpiece provided in its periphery with a plurality of orifices corresponding to the number of pins for removably receiving said pins to form a forming core for a coil having an inner periphery corresponding to the outer periphery of the centerpiece, and a plurality of anchoring members removably secured in position on the periphery of said centerpiece by said pins to form a forming core for a coil having an inner periphery corresponding to the outer periphery formed by said anchoring members.
3. A device of the character described having a plurality of pins, a centerpiece in its periphery provided with a plurality of orifices corresponding to the number of pins for removably receiving said pins to form a forming core for a coil having an inner periphery corresponding to the outer periphery of the centerpiece, and a plurality of anchoring members removably secured in position on the periphery of said centerpiece by said pins to form a plurality of forming cores for coils having inner peripheries corresponding to the outer peripheries formed by said anchoring members.
4. A device of the character described having a plurality of pins, a centerpiece having a cylindrical surface and provided with a plurality of orifices in its periphery corresponding to the number of pins for removably receiving said pins to form a forming core for a coil having an inner periphery corresponding to the outer periphery of the centerpiece, and a plurality of anchoring members removably secured in position on the periphery of said centerpiece by said pins to form a plurality of forming cores for coils having inner peripheries corresponding to the outer peripheries formed by said anchoring members.
5. A device of the character described having a plurality of pins, a centerpiece having a plurality of cylindrical portions adjacent to one another, there being a plurality of orifices in one of said cylindrical portions corresponding to the number of pins for removably receiving said pins to form a forming core for a coil having an inner periphery corresponding to the outer periphery of the cylindrical portion provided with the orifices, and a plurality of anchoring members removably secured in position on the periphery of said centerpiece by said pins to form a plurality of forming cores for coils having inner peripheries corresponding to the outer peripheries formed by said anchoring members, said anchoring members having depending portions engaging one of said cylindrical portions to define the location of the same.
6. A device of the character described, having a centerpiece composed of three cylindrical portions concentric with one another.

other and of different diameters, the intermediate portion having the greatest diameter and provided with a plurality of orifices, anchoring members having depending lugs 5 to engage either of said other cylindrical portions according to the position to be assumed, there being orifices formed in said anchoring members, and a pin extending through the orifices of said anchoring members into said 10 centerpiece to anchor the same in place.

7. A device of the character described having a plurality of pins, a centerpiece having a plurality of orifices for removably receiving said pins to form a forming core for a coil having one diameter, a plurality of anchoring members provided with orifices to receive said pins and to be removably secured in position on the periphery of said centerpiece to form a forming core for a coil
15. having an inner periphery corresponding to the outer periphery defined by said anchoring members, and fixed pins on said anchoring members extending at right angles to the orifices in said anchoring members to form
20. still another forming core for a coil having an inner periphery corresponding to the outer periphery defined by the fixed pins.
- 25.

8. A device of the character described having a plurality of pins, a centerpiece having a plurality of orifices for removably receiving said pins to form a forming core for a coil having one diameter, a plurality of anchoring members provided with orifices to receive said pins and to be removably secured in position on the periphery of said centerpiece to form a forming core for a coil having an inner periphery corresponding to the outer periphery defined by said anchoring members, and fixed pins on said anchoring members extending at right angles to the orifices in said anchoring members to form still another forming core for a coil having an inner periphery corresponding to the outer periphery defined by the fixed pins, each anchoring member having a plurality of inclined faces so that when the anchoring members are mounted on the centerpiece their opposing faces will engage one another and thus align the same in place.

50. 9. A device of the character described having a plurality of anchoring members, a centerpiece having a cylindrical portion, there being orifices formed in said cylindrical portion and extending to the periphery thereof, each anchoring member having two sets of inclined faces, there being an orifice extending through each anchoring member, and securing pins extending through the orifices of said anchoring members into the orifices of said cylindrical portion to secure the anchoring members in place with either of their sets of inclined faces in engagement with one another.

10. A device of the character described
45 having a plurality of securing members, a

centerpiece having a plurality of orifices for removably receiving said securing members to form a forming core for a coil having an inner periphery corresponding to the outer periphery of said centerpiece, a plurality of anchoring members provided with orifices, each anchoring member having a set of inclined faces of one incident of inclination and another set of inclined faces of another incident of inclination, the securing members extending through the orifices of said anchoring members either removably to secure the anchoring members in place with the faces of one incident of inclination in engagement with one another to form another forming core having an inner periphery corresponding to the outer periphery of the anchoring members when so positioned, or removably to secure the anchoring members in place with the faces of the other incident of inclination in engagement with one another to form still another forming core having an inner periphery corresponding to the outer periphery of the anchoring members when so positioned.

11. A device of the character described having a plurality of securing members, a centerpiece having a plurality of orifices for removably receiving said securing members to form a forming core for a coil having an inner periphery corresponding to the outer periphery of said centerpiece, a plurality of anchoring members provided with orifices, each anchoring member having a set of inclined faces of one incident of inclination and another set of inclined faces of another incident of inclination, the securing members extending through the orifices of said anchoring members either removably to secure the anchoring members in place with the faces of one incident of inclination in engagement with one another to form another forming core having an inner periphery corresponding to the outer periphery of the anchoring members when so positioned, or removably to secure the anchoring members in place with the faces of the other incident of inclination in engagement with one another to form still another forming core having an inner periphery corresponding to the outer periphery of the anchoring members when so positioned, each anchoring member having a depending member forming the continuation of one set of inclined faces to engage the centerpiece and to aid in alining the anchoring members when the anchoring members are positioned with said latter set of inclined faces in engagement with one another.

12. A device of the character described having a plurality of securing members, centerpiece having a plurality of orifices for removably receiving said securing members to form a forming core for a coil having an inner periphery corresponding to the outer 100

periphery of said centerpiece, a plurality of anchoring members provided with orifices, each anchoring member having a set of inclined faces, the securing members extending through the orifices of said anchoring members removably to secure the anchoring members in place with said inclined faces in engagement with one another to form another forming core for a coil having an inner periphery corresponding to the outer periphery of said anchoring members when so positioned.

13. A device of the character described having a plurality of securing members, a centerpiece having a plurality of orifices for removably receiving said securing members to form a forming core for a coil having an

inner periphery corresponding to the outer periphery of said centerpiece, a plurality of anchoring members provided with orifices, 20 each anchoring member having a set of inclined faces, the securing members extending through the orifices of said anchoring members removably to secure the anchoring members in place with said inclined faces in 25 engagement with one another to form another forming core for a coil having an inner periphery corresponding to the outer periphery of said anchoring members when so positioned, each anchoring member having a de- 30 pending member forming a continuation of said inclined faces to engage the centerpiece and to aid in alining the anchoring members.

FRANKLIN BITTNER.
